UNITED STATES PATENT OFFICE.

CHARLES HALVERS, OF NEW YORK, N. Y., ASSIGNOR OF ONE-HALF TO HULDA BARRY,
OF NEW YORK, N. Y.

DETACHABLE HEEL.

1,122,107

Specification of Letters Patent. Patented Dec. 22, 1914.

Application filed July 7, 1914. Serial No. 849,478.

To all whom it may concern:

Be it known that I, CHARLES HALVERS, a citizen of the United States, residing at New York, in the county of New York and State of New York, have invented new and useful Improvements in Detachable Heels, of which the following is a specification.

The general object of this invention is to facilitate the securing of a resilient heel to a shoe and to effect the operation without the essential employment of usual cobbler's tools.

Another object is to effect the securing of resilient heels upon shoes in a detachable manner, whereby the heel on a pair of shoes may be readily interchanged and thus prolong the life of the heels by inviting the same to be worn in an even manner. And to these ends the invention consists of a resilient heel having provided therein a plurality of oppositely disposed gripping members which are slidably mounted in the heel and are adapted to bite into the heel portion of a shoe for securing the resilient heel thereon.

Other objects will appear and be better understood from that embodiment of my invention of which the following is a specification, reference being had to the accompanying drawings forming part hereof, in which:

Figure 1 is a longitudinal vertical sectional view of my improved heel mounted on a shoe. Fig. 2 is a top plan view of my improved heel. Fig. 3 is a cross sectional view taken on the line 3--3 in Fig. 2. Fig. 4 is a detail dissected perspective view of the coöperating gripping elements, and Fig. 5 is a detail perspective view of one of the guides for the gripping elements.

As shown in the drawings 5 indicates a resilient heel having arranged on its upper face a longitudinal slot 6 in which is slidably arranged the oppositely disposed gripping members 7 and 8, which coöperate with a locking member 9 and guides 10 and 11 to effect the attachment of the heel to a shoe.

The heel 5 is preferably formed of rubber and is similar in structure and material to the ordinary rubber heel now in use, and obviously may be manufactured in various sizes so as to accommodate the usual sizes of shoes. The heel may be made solid as shown, and provided on one face thereof is a

centrally located longitudinal slotted or countersunk portion 6 which forms a substantial guide slot for the gripping elements 7 and 8 and thus admits of the latter to be positioned flush with the face of the heel. While the heel is being manufactured, it is preferred to provide a textile tablet 12 in the central portion of the heel as shown, the purpose of which will be presently described. The guides or retaining pieces 10 and 11 are positioned within the heel while the heel is being molded or otherwise formed, and thus are embedded in the body of the heel as shown in Figs. 2 and 3.

The guide 10 is shown in detail in Fig. 5, and is preferably formed in one piece, and may be stamped from any suitable metal desired such as steel, brass or the like. The guide has a central arch-portion 13, wherein slidingly operates the element 8, and for the purpose of providing suitable means for anchoring the same within the heel the oppositely disposed ears 14 are provided on either side of the arch 13 as shown. The guide 11 is somewhat similar in structure to the guide 10 and description is unnecessary; the only difference between the two guides being that the guide 11 is curved so as to conform to the outline of the rear of the heel as shown in Fig. 2. The gripping elements 7 and 8 are similar in shape and may be made of any material desired such as steel or the like. These elements have upturned end portions 15 which are provided with teeth 16, which are disposed horizontally on the inner end portions thereof and arranged on portions of the opposite edges of the stems 17 are a series of laterally arranged teeth 18 as shown. The locking member 9 is rectangular in shape and has depending side portions provided with the teeth 19, whereby the same may be positioned within the slot 6 of the heel and driven into the body thereof. It will be seen here that the function of the textile portion 12 is to receive these teeth 19 and retain the same in relatively fixed position, and thus eliminate any possibility of the metallic teeth from becoming disengaged from the rubber. Now, upon the member 9 being positioned within the slot, the upper portion 20 thereof will be in spaced relation with the face of the slot 6, and thus form a guide for the members 7 and 8.

When it is desired to position the heel

upon a shoe, the elements 7 and 8 are drawn apart as shown in Fig. 2, and the heel 5 is mounted on the shoe heel in a manner similar to that shown in Fig. 1. A suitable driving implement such as a hammer or the like is then employed and the gripping members 7 and 8 are driven toward each other, so that the teeth portions 16-16 bite into the leather of the shoe-heel and secure the heel 5 thereon as shown in Fig. 1, and by virtue of the teeth 18 on the stems 17 of the members 7 and 8 engaging the teeth 19 of the member 9, the parts are substantially locked together.

15 It is obvious that those skilled in the art may vary the details of construction and arrangements of parts without departing from the spirit of my invention and therefore I do not wish to be limited to any such 20 features except as may be required by the claims.

What I claim as new is:—

- 25 1. A heel for shoes provided with gripping members movably mounted on opposite ends of the heel and arranged for securing the heel to the shoe and a means for engaging and automatically locking the gripping members in a fixed position substantially as described.
- 30 2. A heel for shoes provided with a pair of pronged gripping members movably arranged on one face thereof, said gripping members mounted on opposite ends of the heel and arranged for securing the heel to the shoe and a means for automatically locking the gripping members in a fixed position when secured to the heel of the shoe.
- 35 3. A rubber heel for shoes provided with pronged gripping members movably mounted on the opposite ends of the heel and arranged for securing the heel to the shoe and a means mounted on the shoe and arranged for engaging the gripping members for locking the same in a fixed position when secured to the shoe.
- 40 4. A rubber heel for shoes provided with gripping members movably arranged on one face thereof, said members mounted on the opposite ends of the heel and a locking

member mounted on the heel and arranged 50 for engaging the gripping members for locking the same in a fixed position for the purpose set forth.

5. A rubber heel for shoes provided with pronged gripping members movably mounted 55 on opposite ends of the heel, and a pronged locking member for engaging the gripping members and arranged for locking the same in a fixed position for the purpose set forth.

6. A rubber heel for shoes provided with 60 movable gripping members mounted on opposite ends of the heel and a pronged locking member mounted on the heel and arranged for engaging the ends of the gripping members for the purpose set forth. 65

7. A rubber heel for shoes having a longitudinal slot arranged in one face thereof, movable gripping members arranged within the slot at the opposite ends of the heel and means for locking the gripping members in 70 a fixed position for the purpose set forth.

8. A rubber heel having guides, gripping members movably mounted within the guides and a locking member mounted in the heel and arranged for engaging the gripping 75 members for the purpose set forth.

9. A rubber heel for shoes having a slot arranged in one face thereof, guides mounted within the slot at opposite ends of the heel and pronged gripping members movably 80 mounted within the guides for engaging the heel of the shoe.

10. A rubber heel for shoes provided with gripping members movably mounted on one face thereof, said gripping members having 85 one end provided with prongs and its opposite ends provided with teeth, and a pronged locking member arranged for engaging the teeth of the gripping member for automatically locking the same in a fixed position 90 when secured to the heel of the shoe.

In testimony whereof I affix my signature in presence of two witnesses.

CHARLES HALVERS.
